CLAIM

The ornamental design for a half torus container bottom, as shown and described.

DESCRIPTION

FIG. 1 is a front view of a container with a half torus container bottom.

FIG. 2 is a side view of the container with a half torus container bottom.

FIG. 3 is a front view of a half torus container bottom.

FIG. 4 is a top plan view of the half torus container bottom.

FIG. 5 is a bottom plan view of the half torus container bottom.

FIG. 6 is a top perspective view of the half torus container bottom.

FIG. 7 is a bottom perspective view of the half torus container bottom.

FIG. 8 is a front section view of the half torus container bottom.

FIG. 9 is a top perspective view of the half torus container bottom; and,

FIG. 10 is a bottom perspective view of the half torus container bottom.

The broken line showing of parts of the drawings is included for the purpose of illustrating portions of a container and forms no part of the claimed design.

1 Claim, 10 Drawing Sheets
